UNITED STATES PATENT OFFICE.

CLIFFORD N. LUSH, OF WINNIPEG, MANITOBA, CANADA.

HEAT ECONOMIZER.

Application filed February 3, 1928. Serial No. 251,683.

The invention relates to improvements in heat economizers and more particularly to a device for use in connection with a hot air heater such as a hot air furnace and an object of the invention is to provide a device which can be readily installed on existing hot air furnaces and which will permit of the effective utilizing of heat customarily wasted in the stack or chimney and which device adds in no way to the operating costs of the furnace.

A further object of the invention is to provide a device inserted in the smoke pipe and entering the air heating chamber of the furnace in a location above the dome and which is constructed when desired to circulate the waste gases through the air chamber to permit them to give off their heat in passage and in so doing materially increase the efficiency of the furnace as a heating unit.

A further object is to construct the device so that the products of combustion can be passed directly to the chimney if desired such as is required when initially starting the fire.

A further object of the invention is to construct the appliance so that it can be installed in existing types of furnaces without requiring to make any material change in the furnace structure.

A further object of the invention is to construct the device in a simple, durable and inexpensive manner and so that it can be readily cleaned as occasion demands.

With the above more important objects in view, the invention consists essentially in the arrangement and construction of parts hereinafter more particularly described, reference being had to the accompanying drawings, in which:

Fig. 1 is a side view of the device as installed in a furnace, the upper portion of the furnace being shown in vertical section.

Fig. 2 is a horizontal sectional view at 2-2' Figure 1.

Fig. 3 is a perspective view of the appliance, parts being broken away to expose interior construction.

Fig. 4 is an enlarged detailed vertical sectional view at 4-4' Figure 3.

Fig. 5 is a perspective view of a portion of one of the tubes.

In the drawings like characters of reference indicate corresponding parts in the several figures.

The furnace herein shown is the customary

hot air furnace and embodies the fire box 1, ash pit 2, combustion chamber 3 and dome 4, the aforesaid parts being contained within an outer casing 5, the outer casing being spaced from the aforesaid parts to provide an air heating chamber 6 surrounding and about the combustion chamber. Heating pipes 7 lead from the upper part of the outer casing and cold air admission pipes 8 lead to the bottom of the casing. A smoke pipe 9 passes from the combustion chamber out the back of the outer casing and is connected to a flue pipe 10. An ash door 11 opens to the ash pit and a fire door 12 opens through the combustion chamber to the fire box. The outer casing is usually made from a number of sheet metal rings which can be stacked one on top of the other, this being for convenience in setting the furnace up in a basement.

The parts hereinbefore described are in common use and form no part of my invention.

When it is desired to install my invention, I lift off the uppermost section or ring of the furnace and insert my heat economizer and then replace the upper ring on top of the economizer which is built to receive it. The economizer is now described in detail.

A circular ring or band 13 is supplied which is of the same diameter as the outer casing, as the band is adapted when installed in the furnace to take a position between the uppermost furnace casing section and the one there below. In other words when I insert my device, I first remove the upper section or ring of the furnace, then place my ring in the position which the top section previously occupied and then remount the top section of the furnace on top of the ring or band 13.

The ring or band 13 carries two diametrically opposing head plates 14 and 15 and these head plates are connected by a plurality of similar tubes 16 which have their ends opening through the head plates. The ends of the tubes must make a gas tight joint with the head plates. By observing Figure 1, it will be seen that there are several horizontal rows of tubes and that the tubes take a position crossing the air chamber 6 in a location directly above the dome of the combustion chamber. Adjoining the head 15, I form a closed passageway 17 connecting the ends of the tubes and hinged doors 18 and 19 are supplied to give entrance to the

passageway from the exterior of the furnace. Suitable means indicated at 20 is provided for releasably fastening the doors closed and the arrangement is such that one can 5 readily approach the tubes for cleaning purposes by opening the doors as will readily be understood.

The rear side of the ring or that remote from the doors carries a box like exterior 10 extension 21 which is vertically divided by a partition 22 and has a further horizontal partition 23 therein. These partitions provide an entry compartment 26, an intermediate compartment 27 and an outlet compartment 25. The vertical partition 22 extends inwardly from the outer side of the box to the head plate 14 and serves to separate or divide the tubes into two series, one series of tubes having their rear ends communicating 15 with the compartment 25 and the other series having their rear ends communicating with the compartment 27. Here it will be observed that the compartment 26 is not in direct communication with the tubes.

20 The lower end of the partition 22 is provided with a hole or passage 28 connecting the compartment 26 with that 25 and the partition 23 is supplied with a hole or passage 29 connecting the compartment 26 with 25. A damper rod 30 is suitably rotatably mounted in the upper inner corner of the compartment 26 and carries a damper 31 which upon rotation of the damper rod can be brought to positions such that it will 30 close the passage 28 or that 29 as selected. The compartment 26 is provided with an inlet passage 32 and when the device is installed on a furnace, this passage communicates with the pipe 10 hereinbefore 35 described.

40 Two outlet passages 33 and 34 lead from the compartment 25 and one or other of these can be used to connect with that part of the smoke pipe leading to the chimney 45 depending on which is the more convenient. In the present instance, the smoke pipe 35 leading from the device to the chimney is shown as connected to the outlet 33 and the outlet 34 is shown as closed by a cap 36. With such an arrangement, one can remove 50 the cap in order to clean out soot or other accumulation in the compartment 25. The end of the box 21 remote from the compartment 25 is supplied with a clean out door 37 and the section 35 of the smoke pipe is provided with a check damper 38. The tubes are provided with a plurality of fins 39 of any approved design.

According to the above construction, it 60 will be apparent that the tubes can be readily cleaned by passing the customary furnace brush through them, the tubes being readily entered after the doors 18 and 19 have been opened. Any deposit in the tubes which may 65 be brushed into the compartments 25 and 27

can be readily cleaned out by opening the door 37 and removing the cap 36.

When a fire is to be built or initially started in the furnace, the check damper 38 is closed and the damper 31 is swung 70 upwardly to close the passage 29 and open that 28. The smoke will then pass directly through the box 21 from the pipe 10 to that 35 as it can escape from the compartment 26 through the passage 28 into the chamber 25. 75 When the fire is burning properly, one will turn down the damper to close the passage 28 and open that 29 at which time the smoke or products of combustion will pass up the pipe 10 into the compartment 26, through 80 the passage 29 into the compartment 27, from the compartment 27 through one of the series of tubes forwardly to the passage 17, from the passage 17 rearwardly through 85 the other series of tubes to the compartment 25 and from the compartment 25 directly through the outlet 33 to the pipe 35. The check damper 38 can of course be regulated as experience dictates.

I have found that by circulating the hot 90 gases in the manner just described through the tubes, I save a great deal of heat which would otherwise be lost in the chimney and that by so doing, I materially increase the heating capacity of the furnace. The device is constructed so that it can be readily placed on existing furnaces without materially altering their structure and once installed, it effects a material saving in fuel 95 due to the increased heating capacity which 100 the furnace will have.

What I claim as my invention is:—

1. A heat economizer for a hot air furnace comprising a box interiorly divided to provide an entry compartment, an intermediate compartment and an outlet compartment, flue pipes connecting the intermediate compartment with the outlet compartment and extending into the upper part of the furnace, a smoke pipe leading the products 105 of combustion from the furnace to the entry compartment, a flue pipe communicating with the outlet compartment and leading to the chimney and damper controlled passages 110 between the entry compartment and the other compartments.

2. A heat economizer for a hot air furnace comprising a box exterior to the furnace and interiorly divided to provide an entry chamber, an intermediate chamber and an outlet chamber and having a smoke passage connecting the inlet chamber with the intermediate chamber and a smoke passage connecting the entry chamber with the outlet chamber, a series of circulating pipes connecting the intermediate chamber with the outlet chamber, said pipes extending horizontally across the furnace within the upper 120 part thereof, a pipe leading the products of combustion from the furnace to the inlet 125 130

- compartment, a pipe connecting the outlet compartment with the chimney and a damper for selectively closing one or other of the passages aforesaid.
5. 3. A heat economizer for a hot air furnace comprising a ring insertible in the upper part of the outer casing of the furnace, diametrically opposing head plates carried by said ring, two sets of tubes connecting the head plates and extending across the upper part of the furnace, a passage connecting the ends of the sets of tubes at the front side of the furnace, a box exterior of the furnace and interiorly divided to provide an inlet compartment, an intermediate compartment and an outlet compartment, said intermediate compartment being in direct communication with the rear ends of one set of tubes and said outlet compartment being in direct communication with the rear ends of the other set of tubes, a pipe leading the products of combustion from the furnace to the inlet compartment, a pipe connecting the outlet compartment with the chimney, a smoke passage connecting the inlet compartment with the intermediate compartment, a smoke passage connecting the inlet compartment with the outlet compartment and a damper for selectively controlling the passage of the smoke from the inlet compartment to the other compartments through said passages.
4. In a heat economizer for hot air furnaces, a ring insertible in the upper part of the furnace casing, two sets of pipes carried by said ring and extending transversely across the upper part of the furnace, said sets of pipes being interconnected at one end and means for selectively passing the products of combustion from the furnace through said sets of pipes prior to their escaping to the chimney.

Signed at Winnipeg, this 11th day of January, 1928.

CLIFFORD N. LUSH.
